FUSE CONSTRUCTION

Sigurd I. Lindell, Chicago, Ill., assignor to
 Schweitzer & Conrad, Inc., Chicago, Ill., a corporation of Delaware

Application August 3, 1940, Serial No. 350,776

18 Claims. (CL 200—135)

This invention relates, generally, to circuit interrupting apparatus, and it has particular relation to the construction of fusible elements for circuit interrupters of the fuse type.

An object of this invention is to provide for definitely and permanently controlling the current division between a low melting point core and a high melting point sheath of a composite fusible element.

A further object of this invention is to provide a fusible element which will maintain substantially constant its time-current characteristics throughout its life.

Another object of this invention is to provide for taking advantage of the properties of silver and tin in a fusible element in a new and improved manner.

Another object of this invention is to prevent alloying between a tin core and a silver sheath of a fusible element.

It is another object of this invention to provide for rapidly conducting heat away from the tin core of a fusible element having a silver sheath and for preventing the conduction of heat to the tin core.

Another object of this invention is to deform relatively infusible terminals onto the ends of a fusible element formed by a tin core having a silver sheath in such a manner that there will be no concentration of stress at the junctions of metallic plugs which fill the ends of the sheath and the abutting ends of the tin core.

It is another object of this invention to form a fusible element comprising a tin core encased in a silver sheath in the form of a coil or spiral.

Other objects of this invention will, in part, be obvious and in part appear hereinafter.

For a more complete understanding of the nature and scope of this invention reference may be had to the following detailed description taken in connection with the accompanying drawings, in which:

Figure 1 is a view, partly in side elevation and partly in section, showing the silver sheath of a composite fusible element;

Figure 1 is a view in side elevation showing the construction of the core that is intended to be fitted into the sheath shown in Figure 1;

Figure 3 is a sectional view of the composite fusible element having terminals at its ends;

Figure 4 shows how a terminal can be deformed onto one end of the composite fusible element;

Figure 5 is a longitudinal sectional view of a replaceable fuse link, certain parts being shown in

elevation, in which is embodied the composite fusible element of the present invention;

Figure 6 is a longitudinal sectional view, certain parts being shown in elevation, of a replaceable cartridge in which the fusible element of the present invention is embodied;

Figure 7 is a view, at an enlarged scale, showing how the fusible element for the cartridge shown in Figure 6 is constructed;

10 Figure 8 is a view illustrating the method of deforming the terminals onto the ends of the fusible element shown in Figure 7;

Figure 9 is a longitudinal sectional view of a portion of a solid material type of fuse in which the composite fusible element of the present invention is embodied;

Figure 10 is a view, at an enlarged scale, showing the details of construction of the fusible element for the fuse shown in Figure 9;

20 Figure 11 is a longitudinal sectional view of a liquid type of fuse in which the composite fusible element of the present invention is embodied;

Figure 12 is a detail sectional view taken along the line 12—12 of Figure 11; and

25 Figure 13 is a detail sectional view taken along the line 13—13 of Figure 12.

The present invention constitutes an improvement over the construction shown in the copending application of Triplett, Serial No. 144,789, filed May 26, 1937.

Referring now particularly to Figures 1, 2 and 3 of the drawings, it will be observed that the reference character 10 designates, generally, a composite fusible element which has a sheath 11 that is formed of relatively high melting point high conductivity metal such as silver. The sheath 11 is shown by itself in Figure 1, and, as there indicated, it may be formed of silver that is dead soft annealed. The sheath 11 may be formed of other material having similar characteristics such as copper. However, silver is preferred.

Within the sheath 11 there is a core that is formed principally of low melting point metal such as tin. The core in its entirety is indicated at 12 in Figure 2 and comprises an intermediate tin core portion 13 to the ends of which imperforate metal plugs 14 are secured at butt joints 15. The plugs 14 are formed of metal which is capable of conducting heat rapidly away from the tin core 13 and which is capable of forming permanent electrical joints of low resistance with the ends of the tin core 13. The plugs 14 are preferably formed of hard drawn silver.

The plugs 14 are secured to the ends of the tin core 13 by heat and fusion. If the plugs 14 are formed of hard drawn silver they can be heated to about 300° C. and then they are placed at the ends of the tin core 13, the abutting faces having been previously cleaned by flux or grinding. Sufficient heat is transferred from the plugs 14 to the ends of the tin core 13 so as to cause the desired fusion at the joints 15. The silver tin alloy joints 15 have approximately the same resistivity as the tin core 13 itself. Therefore, it is unnecessary to consider the resistance of these joints since it is substantially the same, as the resistance of the tin core 13 itself and therefore the resistance of the tin core is determined substantially only by its physical dimensions. This is important when the division of current flow between the sheath 11 and the core 13 is considered.

It is important that there be no alloying action between the tin core 13 and the silver sheath 11 prior to actual operation of the composite fusible element to interrupt a circuit. It is for this reason that the core 12 is assembled separately from the sheath 11. After the core 12 has been assembled and has cooled to room temperature, it is inserted into the sheath 11. The internal diameter of the sheath 11 is just large enough to accommodate the core 12 readily and without a loose fit. The silver plugs 14 at the ends of the tin core 13 within the silver sheath 11 seal the ends of the latter after terminals 16 are deformed thereon and prevent oxidation of the surface of the tin core 13.

The composite fusible element 10 is arranged to inter-connect relatively infusible massive terminals 16. It will be understood that the terminals 16 are merely illustrative of various types of terminals that can be employed in connection with the composite fusible element 10 as will hereinafter appear. Each of the terminals 16 is provided with a longitudinally extending aperture 17 which is of such diameter that the ends of the composite fusible element 10 readily fit therein. The outer ends of the apertures 17 are beveled as indicated at 18 so that sharp corners are not presented to the adjacent surface of the sheath 11.

It will be observed that the apertures 17 are of such depth that the butt joints 15 between the tin core 13 and the silver plugs 14 are well within the solid metal of the terminals 16 as indicated at 19. With this arrangement, when the composite fusible element 10 is flexed or the terminals 16 are moved relatively to each other, there is no stress concentration along the joints 15 since they are fully protected by the terminals 16 themselves. The flexing that takes place will principally be concentrated along the lines where the composite fusible element 10 emerges from the terminals 16 where the section of the core 13 and sheath 11 is homogeneous. With the arrangement above described this line is through the solid tin of the core 13.

The ends of the composite fusible element 10 are preferably secured to the terminals 16 by deforming the latter onto the former. As indicated in Figure 4 of the drawings, the terminal 16 may be inserted in a suitably shaped opening 20 in a die 21 and then a punch 22 is moved downwardly into the opening 20 so as to deform the terminal 16 onto the end of the composite fusible element 10 within the same. This deforming operation provides intimate contact engagement between the terminal 16 and the sheath 11. Also the

sheath 11 is deformed into intimate contact engagement with the plug 14 and a small portion of the tin core 13.

It will be understood that the relative sizes of the silver sheath 11 and the core 12 will vary depending upon the time-current characteristics that are desired. Thus, the sheath 11 and core 12 may be longer than that shown in the drawings or shorter and may have greater or lesser diameters as may be desired.

When the terminals 16 are deformed onto the ends of the composite fusible element 10, there will be intimate contact between the silver plugs 14 and the silver sheath 11. The joints at 15 between the silver plugs 14 and the tin core 13 have a definite resistance which is that of the tin core 13 itself. Thus the tin core 13 and the silver sheath 11 are connected in parallel through joints of low resistance at which no oxidation can take place. Therefore, it is possible to accurately predetermine the time-current characteristics of the composite fusible element 10 since it is possible to determine accurately the division of current flow between the tin core 13 and the silver sheath 11. This is important even though the silver sheath 11 constitutes the principal current carrying element.

For purposes of illustration, the composite fusible element represented by the reference character 10 will be employed in the various embodiments of the invention disclosed. It will be understood, however, that the actual proportions for the different embodiments will be different but for illustrative purposes they can be considered as being the same.

In Figure 5 of the drawings there is shown a renewable or replaceable fuse link construction that is similar to the fuse link construction shown in Triplett application Serial No. 144,789, referred to hereinbefore. In this embodiment of the invention the composite fusible element 10 has terminals 26 and 27 deformed onto its ends as previously described for the terminals 16. The terminals 26 and 27 are also interconnected by a strain wire 28 which is formed of relatively high strength metal such as a nickel-chromium alloy. The strain wire 28 is inserted in the apertures of the terminals 26 and 27 along with the composite fusible element 10 and these terminals are deformed conjointly onto the ends of both the composite fusible element 10 and the strain wire 28 as will be readily understood. The terminal 26 is provided with a flanged head 29 for connection to one line terminal while the terminal 27 is provided with a flexible lead 31 for connection to another line terminal.

In Figure 6 of the drawings there is shown a cartridge for a solid arc extinguishing type of fuse such as that disclosed in the copending application of Triplett, Serial No. 223,175, filed August 5, 1938. The fuse cartridge comprises relatively infusible terminals 34 and 35 that are arranged to be interconnected by a composite fusible element 10 and a strain wire 37 of the character previously described. The terminal 34 is rod-like in character and is arranged to move longitudinally through a bore 38 in sections 39 of solid arc extinguishing material such as boric acid or magnesium borate. The sections 39 of solid arc extinguishing material are enclosed in a sleeve 40 of suitable insulating material. The rod-like terminal 34 is arranged to be connected to one line terminal. A flexible lead 41 is secured to the terminal 35 to permit connection to another line terminal.

In Figure 7 of the drawings, the arrangement of the composite fusible element in the terminals 34 and 35 is more clearly illustrated. In this embodiment of the invention a composite fusible element 10 is coiled intermediate its ends so that for a given distance between the terminals 34 and 35 a considerably greater length of fusible section therebetween is provided. This is desirable in order to obtain certain time-current characteristics. The ends of the composite fusible element 10 and the strain wire 37 are inserted in suitable apertures in the terminals 34 and 35, which are then deformed to secure the desired contact engagement. It will be observed that the terminals 34 and 35 have beveled openings as indicated at 42 and 43 to prevent the application of sharp edges to the silver sheath 11 as previously described.

In Figure 8 of the drawings, the method of deforming the terminal 35 onto the ends of the composite fusible element 10 and the strain wire 37 is illustrated. The terminal 35 is placed in a suitable opening in a die 44 with the composite fusible element 10 and strain wire 37 in place. A punch 45 is then brought down upon the die 44 under sufficient pressure to deform the terminal 35 and cause the metal thereof to flow around the ends of the composite fusible element 10 and the strain wire 37.

In Figure 9 of the drawings there is shown a fuse construction that is also shown in Triplet Patent No. 2,183,728, except for the fusible element 10. As illustrated, the composite fusible element 10 is provided for interconnecting terminals 48 and 49. The terminal 48 is in the form of a metallic fitting which is secured to a metallic sleeve 50 that in turn is clamped to a ferrule 51 which forms one line terminal of the device. The ferrule 51 is secured onto one end of a tubular insulating housing 52. The terminal 49 is rod-like in character and is arranged to be connected by flexible conductors 53 to a ferrule, not shown, at the other end of the housing 52. The rod-like terminal 49 is arranged to move through a longitudinal bore 54 in sections 55 of solid arc extinguishing material, such as boric acid or magnesium borate, under the influence of a coil tension spring 56. The rod-like terminal 49 has a pin 57 projecting transversely through its lower end to which a strain element assembly, shown generally at 58, is connected for preventing movement of this terminal. As illustrated, the strain element assembly 58 is connected to a pin 59 which projects inwardly from the metallic sleeve 50. When the composite fuse element 10 blows on flow of predetermined overcurrent, the entire current flow is transferred to the strain element assembly 58 which parts and permits the rod-like terminal 49 to be withdrawn through the bore 54 as is fully described in Triplet patent referred to hereinbefore.

The arrangement of the composite fuse element 10 in the terminals 48 and 49 is illustrated more clearly in Figure 10 of the drawings. One end of the composite fusible element 10 is inserted in a suitable aperture in the terminal 48 so that the butt joint 15 is fully protected as previously described. The aperture is beveled as indicated at 60 to prevent the presentation of a sharp edge to the silver sheath 11. The terminal 48 is deformed onto the end of the composite fusible element 10 substantially as shown in Figure 4 of the drawings.

It will be noted that the composite fusible element 10 is coiled several times intermediate its

ends so as to provide a relatively great length of fusible element with a relatively short distance between the terminals 48 and 49.

It will be observed that the aperture in the terminal 48 is beveled as indicated at 61 for the purpose set forth hereinbefore. Not only is the terminal 48 generally deformed onto the end of the composite fusible element but also it is locally deformed as indicated at 62 by use of a prick punch.

In Figure 11 of the drawings, there is shown a liquid fuse construction which, except for the composite fusible element 10, is substantially the same as shown in Conrad Patent No. 2,091,430. As illustrated, the composite fusible element 10 and a strain wire 67 are arranged to interconnect relatively infusible terminals 65 and 66. The terminal 66 is carried by a metallic spider 68 which is supported on a metallic ferrule 69 forming one line terminal of the device. The ferrule 69 is secured by suitable means onto one end of an insulating housing 70. The terminal 66 is arranged to be connected by flexible conductors 71 to a ferrule, not shown, in the lower end of the housing 70. The terminal 66 is arranged to be retracted by a coil tension spring 72 when the composite fuse element 10 and the strain wire 67 have blown.

Surrounding the composite fuse element 10 and the strain wire 67 is a tubular arcing chamber 73 that is formed of suitable insulating material. The arcing chamber 73 is carried by a ring 74 of insulation which, as shown, is threaded into the ferrule 69. The terminal 66 carries arms 75, Figure 12, which support a liquid director 76 which, on retraction of the terminal 66 by the spring 72 is arranged to force liquid, contained in the housing 70 to the level shown, up into the arcing chamber 73 for extinguishing the arc that is drawn between the terminals 65 and 66, all of which is described in detail in the Conrad patent referred to hereinbefore.

A composite fuse element 10 is inserted into suitable apertures in the terminals 65 and 66 which are deformed thereon as previously described. The construction for both is illustrated in Figure 13 in connection with terminal 66. As there shown, the aperture in the terminal 66 for receiving one end of the composite fusible element 10 is of sufficient depth so that the butt joint 15 between the tin core 13 and the silver plug 14 is fully protected. The aperture is beveled as indicated at 77 to prevent the application of a sharp edge to the silver sheath 11. Not only is the terminal 66 generally deformed onto the end of the composite fusible element 10 but also it is locally deformed as indicated at 78 by a prick punch.

Since certain further changes can be made in the foregoing constructions and different embodiments of the invention can be made without departing from the scope thereof, it is intended that all matter shown in the accompanying drawings and described hereinbefore shall be interpreted as illustrative and not in a limiting sense.

What is claimed as new is:

1. In a fuse, in combination, a core formed of metal having a relatively low melting point, a sheath formed of metal having a relatively high melting point surrounding said core and extending beyond the ends of the same, and a plug formed of metal having a relatively high melting point filling each end of said sheath and in-

timately bonded to the ends of said core for conducting heat away therefrom.

2. In a fuse, in combination, a core formed of metal having a relatively low melting point, a sheath formed of metal having a relatively high melting point surrounding said core and extending beyond the ends of the same, a plug formed of metal having a relatively high melting point filling each end of said sheath and intimately bonded to the ends of said core for conducting heat away therefrom, and a relatively infusible terminal interfitting with and deformed onto each end of said sheath.

3. In a fuse, in combination, a core formed of metal having a relatively low melting point, a sheath formed of metal having a relatively high melting point surrounding said core and extending beyond the ends of the same, an imperforate plug formed of metal having a relatively high melting point filling each end of said sheath and engaging the ends of said core for conducting heat away therefrom, and a relatively infusible terminal interfitting with and deformed onto each end of said sheath, the deformed portions of said terminals overlapping the ends of said core through a substantial extent whereby flexing of said sheath in the vicinity of the joints between said core and plugs is prevented.

4. In a fuse, in combination, a core formed of metal having a relatively low melting point, a sheath formed of metal having a relatively high melting point surrounding said core and extending beyond the ends of the same, a plug formed of metal having a relatively high melting point filling each end of said sheath and intimately bonded to the ends of said core for conducting heat away therefrom, and a relatively infusible terminal interfitting with and deformed onto each end of said sheath, the deformed portions of said terminals overlapping the ends of said core through a substantial extent whereby flexing of said sheath in the vicinity of the joint between said core and plugs is prevented.

5. In a fuse, in combination, a tin core, a silver sheath surrounding said core and extending beyond the ends of the same, and a plug formed of metal having a relatively high melting point filling each end of said sheath and intimately bonded to the ends of said core for conducting heat away therefrom.

6. In a fuse, in combination, a tin core, a silver sheath surrounding said core and extending beyond the ends of the same, and a silver plug filling each end of said sheath and intimately bonded to the ends of said core for conducting heat away therefrom.

7. In a fuse, in combination, a tin core, a silver sheath surrounding said core and extending beyond the ends of the same, a plug formed of metal having a relatively high melting point filling each end of said sheath and intimately bonded to the ends of said core for conducting heat away therefrom, and a relatively infusible terminal interfitting with and deformed onto each end of said sheath.

8. In a fuse, in combination, a tin core, a silver sheath surrounding said core and extending beyond the ends of the same, a silver plug filling each end of said sheath and engaging the ends of said core for conducting heat away therefrom, and a relatively infusible terminal interfitting with and deformed onto each end of said sheath, the deformed portions of said terminals overlapping the ends of said core through a substantial extent whereby flexing of said sheath

in the vicinity of the joints between said core and plugs is prevented.

9. In a fuse, in combination, a tin core, a silver sheath surrounding said core and extending beyond the ends of the same, a silver plug filling each end of said sheath and intimately bonded to the ends of said core for conducting heat away therefrom, and a relatively infusible terminal interfitting with and deformed onto each end of said sheath, the deformed portions of said terminals overlapping the ends of said core through a substantial extent whereby flexing of said sheath in the vicinity of the joints between said core and plugs is prevented.

10. In a fuse, in combination, a core formed of metal having a relatively low melting point, a sheath formed of metal having a relatively high melting point surrounding said core and extending beyond the ends of the same, and an imperforate plug formed of metal having a relatively high melting point filling each end of said sheath and engaging the ends of said core for conducting heat away therefrom, the composite element formed by said core and sheath being coiled intermediate its ends to provide a section the length of which is substantially greater than the distance between its end portions.

11. In a fuse, in combination, a tin core, an annealed silver sheath surrounding said core and extending beyond the ends of the same, and an imperforate plug formed of metal having a relatively high melting point filling each end of said sheath and engaging the ends of said core for conducting heat away therefrom, the composite element formed by said core and sheath being coiled intermediate its ends to provide a section the length of which is substantially greater than the distance between its end portions.

12. In a fuse, in combination, a tin core, an annealed silver sheath surrounding said core and extending beyond the ends of the same, a silver plug filling each end of said sheath and intimately bonded to the ends of said core for conducting heat away therefrom, and a relatively infusible terminal interfitting with and deformed onto each end of said sheath, the deformed portions of said terminals overlapping the ends of said core through a substantial extent whereby flexing of said sheath in the vicinity of the joints between said core and plugs is prevented, the composite element formed by said core and sheath being coiled intermediate its ends to provide a section the length of which is substantially greater than the distance between its end portions.

13. Method of making a core for a composite fusible element which comprises: securing by heat and fusion relatively high melting point metal plugs to the ends of a relatively low melting point metal core.

14. Method of making a composite fusible element which comprises: securing by heat and fusion relatively high melting point metal plugs to the ends of a relatively low melting point metal core and inserting the plugs and core into a relatively high melting point metal sheath.

15. Method of making a fuse link which comprises: securing by heat and fusion relatively high melting point metal plugs to the ends of a relatively low melting point metal core, inserting the plugs and core into a relatively high melting point metal sheath thereby forming a composite fusible element, and deforming relatively massive metallic terminal onto the ends of the composite fusible element.

16. Method of making a fuse link which comprises: securing by heat and fusion relatively high melting point metal plugs to the ends of a relatively low melting point metal core, inserting the plugs and core into a relatively high melting point metal sheath thereby forming a composite fusible element, and deforming relatively massive metallic terminals onto the ends of the composite fusible element in such manner that the areas of deformation overlap the ends of the core a 10 substantial extent.

17. Method of making a fuse link which comprises: securing by heat and fusion relatively high melting point metal plugs to the ends of a relatively low melting point metal core, inserting the plugs and core into an annealed relatively high melting point metal sheath thereby forming a composite fusible element, and coiling the

5 composite fusible element intermediate its ends to provide a section the length of which is substantially greater than the distance between its end portions.

18. Method of making a fuse link which comprises: securing by heat and fusion relatively high melting point metal plugs to the ends of a relatively low melting point metal core, inserting the plugs and core into an annealed relatively high melting point metal sheath thereby forming a composite fusible element, coiling the composite fusible element intermediate its ends to provide a section the length of which is substantially greater than the distance between its end portions, and deforming relatively massive metallic terminals onto the ends of the composite fusible element.

SIGURD I. LINDELL.
